A. McTERNEN

CHAIR REPAIRING DEVICE

Filed Oct. 8, 1925

Patented May 4, 1926.

1,583,300

UNITED STATES PATENT OFFICE.

ANDREW MCTERNEN, OF ANDOVER, MASSACHUSETTS.

CHAIR-REPAIRING DEVICE.

Application filed October 8, 1925. Serial No. 61,198.

To all whom it may concern:

Be it known that I, ANDREW MCTERNEN, a citizen of the United States, residing at Andover, in the county of Essex and State of Massachusetts, have invented new and useful Improvements in Chair-Repairing Devices, of which the following is a specification.

The object of this invention is to provide 10 a device whereby the owner of a chair, the seat of which has been damaged or removed, may conveniently and quickly render the chair serviceable and impart a neat and desirable appearance thereto.

15 Of the accompanying drawings forming a part of this specification,—

Figure 1 is a plan view of a repairing device embodying the invention, as it appears before application to a chair.

20 Figure 2 is a plan view of the device as attached to a chair, portions of the latter being shown in section.

Figure 3 is a section on line 3—3 of Figure 2, parts being broken away.

25 Figure 4 is a view similar to a portion of Figure 1, showing grommets forming the eyes hereinafter described.

Figure 5 is a view similar to Figure 3, showing on a larger scale the grommets 30 shown by Figure 4.

Figure 6 is a view similar to Figure 4, showing looped reinforcing rods forming the eyes.

Figure 7 is a view similar to Figures 3 35 and 5, showing the rods and eyes shown by Figure 6.

Figures 8 and 9 are fragmentary perspective views, showing modifications.

40 Figure 10 is a fragmentary perspective view, showing an extemporized support for the sheet constituting an element of the improved repairing device.

The same reference characters indicate 45 the same parts in all of the figures.

45 The repairing device in which my invention is embodied is here shown adapted for use in repairing a so-called piazza chair, the frame of which includes upright members *a* and forming marginal portions of a seat frame, horizontal members or rounds *b*, connecting the members *a* and a seat *c*, usually woven from strands of cane and engaged with the members *b*, the seat being shown conventionally by dotted lines in Figure 3.

50 It is to be understood, however, that the original seat *c* may be removed and re-

placed by the sheet member of the repairing device.

It is to be understood also that in case the original seat is removed, an extemporized 60 support for said sheet may be substituted therefor, as hereinafter described.

The repairing device comprises a flexible sheet 12, preferably of canvas, which may be rubberized or otherwise treated, to render it water proof. The sheet when flat, as shown by Figure 1, is formed to cover the usual chair seat and is of greater area than the latter. The sheet is provided with two pairs of marginal flaps forming major 65 portions of the margin of the sheet, and with notches or recesses 13, formed by cutting away the corners of the sheet, said notches conforming to the upright *a*, as shown by Figure 2. Each pair includes a 70 flap 14, at one edge of the sheet, and a flap 15, at the opposite edge.

The device also comprises two series of independent flexible ligatures 16, preferably 75 of copper wire. The ligatures are permanently engaged with the flaps 14, and have free outer end portions. The flaps 15 are provided with eyes which may be variously constructed, as hereinafter described, and are adapted to receive the free end portions 80 of the ligatures 16, and permit sliding endwise movement of said end portions to tension the sheet. When the sheet is flat, the ligatures are extended outward from the flaps 14, as shown by Figure 1.

90 In the embodiment shown by Figures 1, 2 and 3, the flaps 14 are folded and stitched at 14^a, to form pockets 160, in which metal reinforcing rods 17 are inserted. The inner 95 ends of the ligatures 16 are passed through orifices 18 (Figure 1) in the folded flaps 14, and turned back and intertwined at 190 with the main portions of the ligatures, so that loops 19 are formed as shown by Figure 3, the loops bearing on the reinforcing 100 rods which support and distribute the strain caused by the operation of tensioning the sheet.

The flaps 15 are similarly folded to form 105 pockets 20, in which reinforcing rods 21 are inserted for the same purpose.

Orifices 22 (Figure 1), formed in the folded flaps 15, constitute eyes adapted to receive and permit endwise movement of the free end portions of the ligatures.

110 In applying the repairing device to a chair, I first turn the flaps 14 and 15 of one

pair under two of the members *b* of the seat frame, extend the ligatures 16 engaged with the flaps 14, across the frame, insert the free end portions of said ligatures in the eyes 22 of the flaps 15, pull the free ends backward to tension the ligatures and the sheet, and intertwist the free end portions at 24 with the main portions to independently secure the ligatures and maintain the applied tension. The free ends of the ligatures are preferably provided with loops 25, adapted to be engaged by a tensioning tool, such as a hook 26 (Figure 7) provided with a finger-receiving eye or handle 27. The operator, by pulling on the tool, causes the ligature engaged therewith to slide or move endwise through the corresponding eye 22, until the ligature is suitably tensioned. The flaps 14 and 15 of the other pair are then turned under the two other members *b*, and connected by the ligatures engaged with the flap 14, in the manner and by the manipulation above described.

The sheet 12 is now tensioned in two directions and stretched smoothly across the frame, its recesses 13 conforming to the upright members *a*, as shown by Figure 2. The usual seat *c* may remain in place and be covered by the sheet 12, as indicated by Figure 3, the sheet concealing the seat so that blemishes therein are not visible.

If desired, the seat *c* may be entirely removed, and a support for the sheet 12 may be extemporized by engaging crossed wires 27 with the members *b*, as shown by Figure 10, and placing layers 28 of carpeting or other material on the wires, the sheet being then applied, tensioned, and secured as above described.

The constructions shown by Figures 4, 5, 6, 7, 8 and 9 differ from those already described only in minor details.

Figures 4 and 5 show grommets 29, inserted in the pocketed flaps 14, and receiving the looped inner ends 19 of the ligatures, and grommets 30, inserted in the pocketed flaps 15, and constituting the eyes in which the free end portions of the ligatures are inserted and moved endwise.

Figures 6 and 7 show the flaps interrupted by notches 31, each flap including a series of folded spaced apart tongues forming a series of alined pockets. The inner ends of

the ligatures are engaged with bends 32 of reinforcing wires 33, inserted in the pockets 55 of the flaps 14. The pockets of the flaps 15 are provided with a reinforcing wire 34, having bends 35, constituting the eyes in which the free end portions of the ligatures are inserted and moved endwise. 60

Figure 8 shows a portion of a flap 14, provided with folded spaced apart tabs 36, in which a reinforcing rod 37 is inserted. With the rod 37 are engaged separately formed loops or bends 38, with which the inner ends 65 of the ligatures are engaged.

Figure 9 shows a slight variation from Figure 8, the flap 14 being formed as shown by Figure 6, and the reinforcing rod 39, inserted in the spaced apart pockets, being provided with separately formed loops or bends 40, with which the inner ends of the ligatures are engaged. 70

It will be seen that each ligature 16 may be tensioned and fastened independently of the others, so that breakage of any ligature will not affect the others.

I claim:

For use with a chair which includes corner uprights, and frame members connected with the uprights and forming marginal portions of a seat frame; a repair device comprising a flexible sheet formed to cover the opening bounded by said frame and provided with two pairs of flaps forming major portions of the margin of the sheet and with corner recesses between the flaps, forming minor portions of said margin, each flap having a hemmed free edge, a reinforcing rod in each of said hems, the flaps of each pair being adapted to be folded inwardly under two opposite frame members, and the corner recesses being adapted to conform to the uprights; and two series of independent flexible ligatures fixed at their inner ends to two contiguous flaps around said rods, the other two contiguous flaps being provided with eyes in said hems in which said ligatures are insertable around said rods to tension the sheet in two directions, the ligatures being adapted to be independently secured after tensioning the sheet, to maintain the tension. 85

In testimony whereof I have affixed my signature.

ANDREW McTERNEN.
